UNITED STATES PATENT OFFICE.

RUDOLF WALKER, OF VIENNA, AUSTRIA.

INTERNAL-COMBUSTION ENGINE.

Application filed January 25, 1924. Serial No. 688,527.

To all whom it may concern:

Be it known that I, RUDOLF WALKER, a subject of the Kingdom of Great Britain, residing at Vienna, Austria, have invented 5 Improvements in and Relating to Internal-Combustion Engines, of which the following is a specification.

The present invention relates to internal combustion engines. The object of the invention is to simplify the construction of internal combustion engines, more particularly of internal combustion engines operated with injection of fuel, by the control of the engine being derived from a separately 10 journalled control shaft, which is common to the fuel pumps and fuel valves and by the axial displacement of which produced by the action of the governor the operation of the engine is regulable at the various 15 speeds of revolution.

In the accompanying drawing wherein an approved embodiment of the invention as applied to a two cylinder two stroke cycle engine is shown,

25 Fig. 1 is a longitudinal section of the invention,

Fig. 2 is a plan view, partly in section, the sectional portion of the view being taken on the line B—B of Fig. 3.

30 Fig. 3 is a cross section on the line A—A of Fig. 1 and,

Fig. 4 is a fragmentary end elevation as seen from the right of Fig. 1.

1 is the control shaft, on which the cams 35 2, 3 for the fuel pumps 4, 5 and the cams 6, 7 for the fuel injection valves are mounted. The control shaft 1 is coupled in the axial direction with the governor shaft 8 in such a manner that it is capable of being displaced relatively to the latter, such displacement being capable of at least controlling the fuel pump. In the constructional example shown in the drawing the fuel pump cams 2, 3 are tapered, so that through the 40 axial displacement of the cam shaft the delivery of the fuel pumps may be varied by the length of stroke of the fuel pump pistons being varied. The coupling of the control shaft 1 with the tubular governor shaft 8 is effected by means of roller-shaped driving members 10, between which a fork-shaped intermediate member 11 fixed to the control shaft is guided by means of the prongs 12 for facilitating by rolling friction the displacement of the control shaft. The control 45 shaft is spring controlled in such a manner

that the governor can bring about a displacement of the control shaft only after overcoming the resistance of the spring, which is adjustable. In the drawing a fork 14 60 engages the control shaft by means of a bolt 13, the said fork being loaded by a spring, which is capable of being tightened and slackened and acts in opposition to the governor.

On the governor shaft 8, preferably outside the casing enclosing the control means and the governor, a stepped worm 15 is provided for automatically putting into operation the working and auxiliary cylinders 70 which are started by the reduction of the compression resistances. The stepped worm 15 co-acts with a worm roller 16 which is journalled in a forked lever 17 mounted on a compression relief shaft 18, on which levers 19, 19 are provided for operating rods 20 for closing the air outlet valves not shown. By turning the decompression shaft 18, the engine is changed from the starting position, in which the air outlet valves are open, to 80 the operative position of the engine, in which the air outlet valves are closed. The turning of the decompression shaft is effected by the worm roller 16, which before starting up is brought into engagement with the outermost convolution of the thread of the step of greatest diameter of the worm 15.

After a number of revolutions corresponding to the number of convolutions of the thread, the roller ceases to engage with the greater 90 step, but engages with the smaller step, whereby a rotary impulse is imparted to the decompression shaft 18, by which one of the decompression valves is closed, while the decompression valve of the second cylinder is not closed, until the roller 16 ceases to engage with the last convolution of the worm, so that the working cylinders with the corresponding auxiliary cylinders are brought not simultaneously but after a different number of revolutions automatically from decompression into the normal operative state.

For varying the commencement of the injection of fuel independently of the position of the control shaft an eccentric shaft 21 and eccentric rods 22 are provided, which engage pivoted members 23 of the valve rod work, which form the support for rollers 24 coacting with the valve cams 6, 7, so that, 105 by turning the eccentric shaft, the rollers 24 can be removed from the cams 6, 7, and

the commencement of opening can thereby be adjusted.

In the case of engines, which are to run at greatly varying speeds of revolution, such as engines for vehicles the arrangement may be thus, that by the displacement of the control shaft the moment of opening of the injection valves is altered automatically corresponding to the number of revolutions at 10 the time in such a manner that fuel injection earlier, when the number of revolutions is high than when the number of revolutions is low, namely, commences independently of the quantity of fuel corresponding 15 to the load at any time sooner. This may be effected by the control cams 6, 7 of the injection valves being made tapered.

What I claim is:

1. In an internal combustion engine, a 20 governor shaft, means supporting said shaft and preventing axial displacement thereof, a cam shaft, a governor adapted to displace the cam shaft axially, said cam shaft and governor shaft being arranged in line one 25 behind the other, means independent of the governor shaft supporting the cam shaft, and a coupling between the cam shaft and the governor shaft.
2. In an internal combustion engine, a 30 governor shaft mounted to prevent axial displacement thereof, a cam shaft, and a governor adapted to displace the cam shaft axially, said cam shaft and governor shaft being arranged in line one behind the other, 35 a housing for the cam shaft and governor shaft, fuel pumps mounted on said housing, and means actuated by the cam shaft for

operating the fuel pumps and also mounted on said housing.

3. An internal combustion engine, a governor shaft mounted to prevent axial movement thereof, a cam shaft, a governor shaft adapted to displace the cam shaft axially, said cam shaft and governor shaft being arranged in line one behind the other, fuel pump and fuel injection valve operating cams carried by and displaceable with the cam shaft, and means independent of the cam shaft for variably controlling the operation of a fuel injection valve whereby to vary the moment of injection of the fuel into the combustion engine.

4. An internal combustion engine as claimed in claim 2 characterized by the provision of fuel pump and fuel injection valve operating cams carried by and displaceable with the cam shaft, and means independent of the cam shaft for variably controlling the operation of a fuel injection valve whereby to vary the moment of injection of the fuel into the combustion engine.

5. An internal combustion engine, a governor shaft mounted to prevent axial movement thereof, a cam shaft, a governor shaft adapted to displace the cam shaft axially, said cam shaft and governor shaft being arranged in line one behind the other, a coupling between the cam shaft and governor shaft including roller shaped driving members.

In witness whereof I have hereunto signed my name.

RUDOLF WALKER.
